CLAIM

The ornamental design for a travel toothbrush, as shown and described.

DESCRIPTION

FIG. 1 is a perspective view of a travel toothbrush with the cap on;

FIG. 2 is a front, rear, left and right view of the travel toothbrush with the cap on;

FIG. 3 is a top plan view thereof with the cap on;

FIG. 4 is a bottom plan view thereof with the cap on;

FIG. 5 is a perspective view of the travel toothbrush with the cap off;

FIG. 6 is a perspective view of the toothbrush thereof;

FIG. 7 is front elevational view of the toothbrush thereof;

FIG. 8 is a rear elevational view of the toothbrush thereof;

FIG. 9 is a left side elevational view of the toothbrush

thereof;

FIG. 10 is a right side elevational view of the toothbrush

thereof;

FIG. 11 is a top plan view of the toothbrush thereof; and,

FIG. 12 is a bottom plan view of the toothbrush thereof.

The broken lines shown in the drawing views are included

for the purpose of showing environmental structure that

forms no part of the claimed design.

1 Claim, 10 Drawing Sheets
